US00D988220S

(12) **United States Design Patent** (10) **Patent No.:** **US D988,220 S**
(45) **Date of Patent:** **** Jun. 6, 2023**

(54) **MANIFOLD**

(71) Applicant: **Holley Performance Products, Inc.**,
Bowling Green, KY (US)

(72) Inventors: **Luke Embry**, Rockfield, KY (US);
William Clack, Alvaton, KY (US); **Coy Hudnall**, Bowling Green, KY (US);
Kevin Tracy, Port Charlotte, FL (US)

(73) Assignee: **Holley Performance Products, Inc.**,
Bowling Green, KY (US)

(**) Term: **15 Years**

(21) Appl. No.: **29/718,592**

(22) Filed: **Dec. 26, 2019**

(51) LOC (14) Cl. **12-16**

(52) U.S. Cl.

USPC **D12/194**

Primary Examiner — Michael A. Pratt

(74) Attorney, Agent, or Firm — Dinsmore & Shohl LLP

(57) **CLAIM**

The ornamental design for a manifold, as shown and described.

DESCRIPTION

FIG. 1 is an upper perspective view of a design of a manifold;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1; and,

FIG. 8 is a lower perspective view of the design of FIG. 1. The broken lines shown in the drawings are included for the purpose of illustrating the unclaimed boundary and unclaimed portions of the manifold. The broken lines form no part of the claimed design.

1 Claim, 8 Drawing Sheets
